The ornamental design for a pager, as shown and described.

DESCRIPTION

FIG. 1 is a perspective view of a pager showing our new design;

FIG. 2 is a top view thereof;

FIG. 3 is a front view thereof;

FIG. 4 is a side view thereof;

FIG. 5 is another side view thereof;

FIG. 6 is a back view thereof; and,

FIG. 7 is a bottom view thereof.

The broken line showing on FIGS. 1-6 is for illustrative purposes only and forms no part of the claimed design.

1 Claim, 5 Drawing Sheets—FIG.—1
